UNITED STATES PATENT OFFICE.

PHILLIPS THOMAS, OF EDGEWOOD, PENNSYLVANIA, ASSIGNOR TO WESTINGHOUSE ELECTRIC & MANUFACTURING COMPANY, A CORPORATION OF PENNSYLVANIA.

ELECTRODE HOLDER FOR GLOW-DISCHARGE TRANSMITTERS.

Application filed May 7, 1923. Serial No. 637,053.

My invention relates to telephone systems and apparatus having particular reference to the mechanism required for sound wave translating devices.

5 Broadly speaking, the object of my invention is to provide a supporting capsule for the electrodes required by a glow discharge transmitter.

An object of my invention is to provide a 10 support for the electrodes of the glow discharge telephonic transmitter which will hold them in proper position for operation and which will also fit conveniently into a suitable supporting and protecting case, as 15 described in the co-pending application of Louis F. Kindermann, Serial No. 637,052 filed May 7, 1923, in such way as to be conveniently removed and replaced when conditions of operation require a different set 20 of electrodes.

In my co-pending application Serial No. 600,822, filed Nov. 14, 1922, is described a principle of operation and essential structure for applying that principle whereby a 25 glow discharge is made to serve as a telephone transmitter when connected to suitable circuits and placed in the path of the sound waves. It is desirable for the best operation of this device that the electrodes 30 between which the glow discharge is maintained be supported in a detachable structure which in operation is enclosed in a suitable protecting case. It is necessary that 35 the electrodes between which the glow discharge takes place be supported in proper alignment.

I do this by means of a tube of insulating material, for which use, I find the material known as micarta to be satisfactory, al- 40 though other materials may be used.

Other objects and applications of my invention as well as details of construction will be apparent from the following description when taken in connection with the accompanying drawing, wherein

Figure 1 is a front view of my apparatus, and

Fig. 2 is a vertical section of the same apparatus on the line II-II of Fig. 1.

50 In the drawing, a micarta tube 1 serves as a framework for a glow-discharge device. Through a hole in the tube, drilled at right angles to the axis of the tube, is

mounted a stud 2 carrying an electrode 3 which is held in proper location by nuts 4 55 and 5.

Diametrically opposite the hole in which the stud 2 is mounted, is drilled a second hole for carrying a similar stud 6 which is held in place similarly to stud 2 by nut 7 60 and threaded insulating collar 8. The stud 6 terminates in an electrode 10 similar to the electrode 3. In the same plane and at right angles to the aforementioned holes in which are supported studs 2 and 6, is drilled a 65 third hole for the admission of third stud 9 which is supported in a manner similar to studs 2 and 6 by nuts 11 and 12. Insulating collar 8 carries at its upper end a control element 14 which is connected by wire 15 70 to stud 9.

In operation, the glow discharges take place between electrode 3 and electrode 10 which are held in proper relative position by the aforementioned clamping nuts and 75 micarta tube 1. The sensitizing element 14 is held in operative position by insulating collar 8. This construction provides a transmitter capsule which is sufficiently rigid to hold the electrodes in proper alignment and to meet the other demands placed upon it, and which also can be supported in a case by spring clips fittings on studs 2, 6 and 9, under which conditions it is very 80 readily removed and replaced in its supporting clips.

In order to insure that the discharge will be a glow discharge and will continue to be a glow discharge and not change into an arc, I find that the source of potential must 90 be high and that a current limiting device must be used. In one specific embodiment of my invention I employed a source of somewhat more than 4000 volts with a resistance in series between it and the discharge device of approximately one megohm. In another specific embodiment of this invention I employed a source of 4200 volts together with a current limiting device which 95 restricted the current to one millimeter. 100 The current limiting device used in this instance was a saturation tube.

A characteristic difference between the glow discharge and the arc is found in the relation of current to voltage. In the arc 105 the current is much greater and the voltage

much smaller than in the glow discharge. Another characteristic difference is that with the glow discharge the electrodes are relatively cool, never becoming incandescent, 5 while with an arc the electrodes are hot and the cathode is usually more incandescent than any portion of the arc itself.

By the construction which is described and by modified constructions which will 10 readily be apparent to those skilled in the art, it is possible to provide a convenient supporting and insulating structure for the capsule of a glow-discharge transmitter.

While I have shown only one embodiment 15 of my invention in the accompanying drawings it is obvious that many changes and modifications may be adopted without departing from the spirit thereof. It is desired, therefore, that only such limitations 20 shall be imposed upon my invention as are indicated in the prior art or set forth in the appended claims.

I claim as my invention:

1. A glow discharge transmitter capsule, 25 comprising a cylindrical portion of insulating material open to the air at its ends and glow discharge electrodes attached thereto in operative relation.

2. A glow discharge transmitter capsule, 30 comprising a cylindrical body portion of insulating material and inserted metallic elec-

trodes for carrying said glow discharge, said metallic electrodes affording means by which the capsule may be secured in place.

3. A glow discharge transmitter capsule, 35 comprising a body portion, of insulating material, and a plurality of electrodes inserted in and carried by said body portion and held thereby in operative relation to each other, said electrodes affording means by which the capsule may be secured in place and also whereby the necessary electrical connections may be made.

4. In a glow discharge device, a cylindrical holder, a set of electrodes mounted in 45 the wall thereof and means for independently adjusting the electrodes radially.

5. In a glow discharge device, an insulating holder, a set of electrodes mounted in 50 the wall thereof, two of said electrodes being in alignment, and means for adjusting said electrodes independently of each other.

6. In an open-air, glow-discharge device, a cylindrical holder, electrodes mounted at 55 diametrically opposite points in the wall thereof, a collar surrounding one of said electrodes and a third electrode carried by said collar.

In testimony whereof, I have hereunto 60 subscribed my name this 27th day of April, 1923.

PHILLIPS THOMAS.
